COMBINED MOTOR MOUNT AND TRANSMISSION HOUSING FOR A ROTARY TILLER OR THE LIKE

Kenneth A. Hotz, Sheboygan, and John W. Davies, Milwaukee, Wis., assignors to Gilson Bros. Co., Plymouth, Wis., a corporation of Wisconsin

Original application Sept. 23, 1960, Ser. No. 62,254. Divided and this application July 10, 1961, Ser. No. 66,627

Term of patent 14 years

(Cl. D35—2)

FIG. 1 is a front perspective view taken from the top and one side of a combined motor mount and transmission housing for a rotary tiller or the like embodying our new design;

FIG. 2 is an enlarged front elevational view thereof, the rear being substantially open;

FIG. 3 is an enlarged top plan view thereof; and

FIG. 4 is an enlarged elevational view taken from the side shown in FIG. 1, the opposite side being a mirror image thereof.

The broken-line representation of a motor in FIG. 1 is for purposes of illustration only.

This is a division of our copending application Serial No. D. 62,254, filed September 23, 1960, now abandoned.

We claim:

The ornamental design for a combined motor mount and transmission housing for a rotary tiller or the like, as shown and described.
